(57) **CLAIM**

The ornamental design for a switch for headphones substantially as shown and described.

DESCRIPTION

FIG. 1 is a front perspective view of a switch for headphones showing the new design.

FIG. 2 is a top plan view thereof.

FIG. 3 is a bottom plan view thereof.

FIG. 4 is a left elevation view thereof.

FIG. 5 is a right elevation view thereof.

FIG. 6 is a front plan view thereof.

FIG. 7 is a back plan view thereof.

FIG. 8 is a perspective view of the switch for headphones.

FIG. 9 is a front perspective view the switch for headphones.

FIG. 10 is a top plan view thereof.

FIG. 11 is a bottom plan view thereof.

FIG. 12 is a left elevation view thereof.

FIG. 13 is a right elevation view thereof.

FIG. 14 is a front elevational view thereof.

FIG. 15 is a back elevational view thereof.

FIG. 16 a front perspective view with an unclaimed user finger holding the switch in an upward position to depict the ornamentation of the switch when held in an upward position.

FIG. 17 is a front perspective view with an unclaimed user finger holding the switch in a downward position to depict the ornamentation of the switch when held in a downward position.

FIG. 18 is a front perspective view thereof.

FIG. 19 is a front perspective view the switch for headphones.

(Continued)

FIG. 20 is a top plan view thereof.

FIG. 21 is a bottom plan view thereof.

FIG. 22 is a left elevation view thereof.

FIG. 23 is a right elevation view thereof with a cutaway to show the switch.

FIG. 24 is a right elevation view thereof without a cutaway.

FIG. 25 is a front elevational view thereof.

FIG. 26 is a back elevational view thereof.

FIG. 27 is a front perspective view with an unclaimed user finger holding the switch in an upward position to depict the ornamentation of the switch when held in an upward position.

FIG. 28 is a front perspective view with an unclaimed user finger holding the switch in a downward position to depict the ornamentation of the switch when held in a downward position.

FIG. 29 is a front perspective view of the switch for headphones thereof, the square over the ear headphone is environment in which the design resides.

FIG. 30 is a front perspective view the switch for headphones.

FIG. 31 is a top plan view thereof.

FIG. 32 is a bottom plan view thereof.

FIG. 33 is a left elevation view thereof.

FIG. 34 is a right elevation view thereof with a cutaway to show the switch.

FIG. 35 is a right elevation view thereof without a cutaway.

FIG. 36 is a front elevational view thereof.

FIG. 37 is a back elevational view thereof.

FIG. 38 is a front perspective view with an unclaimed user finger holding the switch in an upward position to depict the ornamentation of the switch when held in an upward position.

FIG. 39 is a front perspective view with an unclaimed user finger holding the switch in a downward position to depict the ornamentation of the switch when held in a downward position.

FIG. 40 is a front perspective view of the switch for headphones thereof, in an over the ear headphone environment in which the design resides.

FIG. 41 is a front perspective view of the switch for headphones thereof;

FIG. 42 is a top plan view thereof.

FIG. 43 is a bottom plan view thereof with a cutaway to show the switch.

FIG. 44 is a bottom plan view thereof without a cutaway.

FIG. 45 is a left elevation view thereof.

FIG. 46 is a right elevation view thereof.

FIG. 47 is a front elevational view thereof.

FIG. 48 is a back elevational view thereof.

FIG. 49 is a front perspective view with an unclaimed user finger holding the switch in an upward position to depict the ornamentation of the switch when held in an upward position; and,

FIG. 50 is a front perspective view with an unclaimed user finger holding the switch in a downward position to depict the ornamentation of the switch when held in a downward position.

The broken lines, in the drawing of FIGS. 1 through 50, depict portions of the switch for headphones and environ-

ment in which the design resides; the broken lines form no part of the claimed design.
